YARN HOLDER FOR MANUALLY KNITTING
MULTICOLORED ARGYLE SOCKSEdna Fitts, Asheville, N. C., and Mary Stringfield
Allen, Burlington, Vt.

Application March 1, 1949, Serial No. 79,008

1 Claim. (Cl. 242—146)

1

This invention relates to a yarn holder for manually knitting multicolored articles such as argyle socks. In this operation the knitter must use and control a number of balls of yarn at the same time. Without some form of mechanical aid, even a skillful knitter has difficulty in manipulating the balls and strands of yarn and in preventing the unraveling of the balls and the tangling of the yarn. The extent to which aid may be given is restricted by the fact that the weaving of the various colored strands requires mobile balls of yarn.

The mechanical aids customarily used consist of devices on which the balls of yarn are wrapped. These devices, which take a number of forms, provide means for gripping the strand of yarn so that the knitter, after using a particular ball of yarn which is wrapped around one of these devices, adjusts the strand in the gripping means thus preventing the ball of yarn from unraveling. In the usual knitting operation, the knitter holds the balls, whether wrapped on these devices or not, in her lap or in the ordinary knitting bag and the control and manipulation of the balls and the numerous strands of yarn drawn therefrom are left to her individual dexterity.

One of the main objects of our invention is to provide means for holding the balls of yarn and for controlling the drawing of the strands of yarn from the balls of yarn in such a manner that not only are the balls of yarn prevented from unraveling but also they are retained in an orderly, relatively stationary position with each ball of yarn maneuverable without disturbing the order or disposition of the other balls of yarn.

In accordance with our invention, a box is partitioned into a number of compartments and is provided with twin covers having openings through which strands of yarn are drawn in the knitting operation from balls of yarn stored in the compartments. The structure of the twin covers is such that the knitter may reach and handle the ball of yarn in any compartment without moving the balls in the other compartments. This arrangement not only prevents the unraveling of the balls of yarn but also facilitates the control and manipulation of the strands without limiting the mobility of the balls and provides a convenient and practical way to store the yarn when not in use.

Briefly described, our yarn holder comprises a box, the interior of which is partitioned into a plurality of compartments, twin covers hingedly connected to the box and disposed for covering relation with the compartments, and semi-circu-

lar openings spaced in the extending edges of the twin covers, whereby circular openings disposed in spaced relation to the compartments are formed by the closing of the twin covers.

5 In beginning to knit manually multicolored articles such as argyle socks, the knitter first casts the basic colored strand of yarn on the needle. When the pattern or argyle is to be woven into the fabric, a varying colored strand of yarn is cast on the needle and the basic colored strand of yarn is left hanging down from the fabric. This procedure is repeated, as the design requires, in knitting across a row, with the number of strands used depending on the complexity of the desired pattern.

10 In purling and knitting subsequent rows, the various depending strands of yarn are used and re-used. In changing from one colored strand to another it is necessary that the ball may be moved under and around the previously used strand. In using our invention in this operation, the knitter, by lifting either or both of the twin covers, may maneuver one or more balls of yarn without disturbing the order or disposition of the other balls.

15 Our invention is described more in detail below in connection with the accompanying drawings, in which:

Fig. 1 is a perspective view of the yarn holder 30 with the twin covers in closed position, and a portion of an argyle sock being knitted;

20 Fig. 2 is a perspective view of the yarn holder with the twin covers in open position; and

25 Fig. 3 is a vertical cross-section taken on line 3—3 of Fig. 1.

30 Referring now to the several figures in the drawings, they illustrate a yarn holder 10 arranged in accordance with the present invention. It has a conventional, rectangular box 40 shape with a bottom 11, side walls 12, end walls 13, and twin covers 14. The interior 15 is divided by partitions 16 into compartments 17 disposed in collateral rows and adapted for receiving balls of yarn 18. The twin covers 14 are connected to the yarn holder 10 by hinges 19 positioned on the upper edges 20 of the side walls 12. The twin covers 14 are disposed for covering relation with the compartments 17.

35 As shown in Fig. 2, semi-circular openings 21 are spaced in the extending edges 22 of the twin covers 14. Upon the closing of the twin covers 14, opposed semi-circular openings 21 merge, as illustrated in Fig. 1, to form circular openings 23. Each of these openings is disposed in spaced relation to two adjacent compartments

17 and each of the compartments 17 is adapted to receive one of the balls of yarn 18.

In the knitting operation, the balls of yarn 18 are placed in the compartments 17, and the strands of yarn 24 are drawn from the balls of yarn 18 and are trained through the circular openings 23. Upon the lifting of either or both of the twin covers 14, one or more of the balls of yarn 18 and strands of yarn 24 may be moved in any desired manner without disturbing the other balls of yarn 18 and strands of yarn 24.

Thus our invention, as above described, comprises a simple yet handy device for effectively controlling and manipulating the balls and strands of yarn in manually knitting multi-colored articles such as argyle socks.

We claim:

A yarn holder for manually knitting multi-colored argyle socks comprising a rectangular box having longitudinally and transversely disposed interior partitions, said partitions forming a plurality of compartments disposed in twin collateral rows in the interior of said box, each compartment being adapted for receiving a ball of yarn, and a top comprising twin covers hinged on the upper edges of the side walls of the box and disposed for covering relation with said compartments, said twin covers being provided in their extending edges with a plurality of meeting

semi-circular openings forming circular openings in said top intermediate its sides and longitudinally thereof, each of said circular openings being disposed in spaced relation to at least two adjacent compartments of said twin rows so that twin strands of yarn drawn from said adjacent compartments may be trained through each of said circular openings, and whereby, upon the opening of one or both of said twin covers, balls and strands of yarn may be maneuvered in the knitting operation without moving the position of the remaining balls and strands of yarn retained in said holder.
